INFLATABLE SUN HATS

Emil Platzke, Minneapolis, Minn.

Application May 14, 1956, Serial No. 41,469

Term of patent 14 years

(Cl. D3—13)

FIG. 1

FIG. 3

Fig. 1 is a perspective view of the under side of an inflatable sun hat showing my new design;

Fig. 2 is a top plan view thereof on a smaller scale; and
Fig. 3 is a bottom plan view thereof.

I claim:

The ornamental design for an inflatable sun hat, substantially as shown.
